UNITED STATES PATENT OFFICE.

LYDIA FAIRWEATHER, OF RICHMOND HILL, NEW YORK.

COMBINED CLOTHES-HORSE AND IRONING-BOARD.

SPECIFICATION forming part of Letters Patent No. 408,471, dated August 6, 1889.

Application filed April 24, 1889. Serial No. 308,437. (No model.)

To all whom it may concern:

Be it known that I, LYDIA FAIRWEATHER, of Richmond Hill, in the county of Queens and State of New York, have invented a new 5 and Improved Combined Clothes-Horse and Ironing-Board, of which the following is a full, clear, and exact description.

The object of the invention is to provide a new and improved combined clothes-horse 10 and ironing-board, which is very simple and durable in construction, can be conveniently set up in any desired place, and folded up when not in use, so as to be out of the way.

The invention consists of certain parts and 15 details and combinations of the same, as will be fully described hereinafter, and then pointed out in the claims.

Reference is to be had to the accompanying drawings, forming a part of this specification, 20 in which similar letters of reference indicate corresponding parts in all the figures.

Figure 1 is a perspective view of the improvement as set up ready for use. Fig. 2 is a front view of the same as folded up, and 25 Fig. 3 is a side elevation of the same.

The combined clothes-horse and ironing-board A is provided with a main frame B, preferably fastened by suitable means to a wall. The frame B is provided with standards C and C', connected at the top by a cross-beam D, near the middle by a cross-beam E, and near the bottom by a cross-beam F. On the standards C and C', between the cross-beams D and E, are pivoted the clothes-frames 30 G and G', each made of two parallel standards G² and G³, connected with each other by rods G⁴, on which the clothes are hung when the said frames are swung open, as shown in Fig. 1.

On the cross-beam E are secured the notched brackets H, in which fit pins I, projecting 40 from the wide end of the ironing-board J, of suitable size and the usual form. On the outer end of the ironing-board J, on the under side, are formed dovetailed cleats K, extending 45 transversely, in which is mounted to slide a dovetail L, on which is hinged the leg N, provided on its lower end with a foot O, hinged to the said leg N. The foot O can be folded 50 up against the leg N, as shown in Figs. 2 and

3, or set at right angles to the leg N, as shown in Fig. 1.

On the lower cross-beam F are secured the notched brackets P, adapted to be engaged by the pins I on the ironing-board J when 55 the latter is to be folded up against the frame B, as shown in Figs. 2 and 3.

On the upper cross-beam D is pivoted a button Q, for securely locking the ironing-board J in place on the frame B when the device 60 is not in use, and as illustrated in Figs. 2 and 3. On the cross-beam E, under the brackets H, is secured a cleat E', on which rests the inner end of the ironing-board J when in use. This takes off all strain of the 65 ironing-board on the brackets H.

The operation is as follows: The frame B is preferably secured to the wall of a room, with the standards C and C' resting on the floor. When the ironing-board J is to be used, its 70 pins I are placed in the notches of the brackets H, and then the ironing-board J is extended horizontally, the leg N being swung down into a vertical position to rest on the floor of the room. The foot O is set at right 75 angles to the leg, so as to give the leg additional support. The frames G and G' can now be swung open and clothes hung on them, after being ironed on the board J. The leg N can be temporarily removed in order to 80 pass articles over the ironing-board J, after which the leg is again put in place and the ironing of the article can proceed in the usual manner.

When the device is not to be used, the 85 empty frames G and G' are moved inward into the position shown in Figs. 2 and 3, and then the ironing-board J is disconnected from the brackets H, after which the pins I are inserted in the notches in the brackets P, and 90 the ironing-board is swung into a vertical position against the fronts of the frames G and G'. The upper end of the ironing-board J is then locked in place by the button Q, and the leg N, on account of being hinged to the 95 dovetail L, swings downward into a vertical position and rests on the back of the ironing-board J, the foot O having been previously folded against the leg N. Thus it will be seen that the entire device is very simple in con- 100

struction, and can be readily set up for use or folded up, so as to be out of the way.

Having thus described my invention, what I claim as new, and desire to secure by Letters Patent, is—

1. A combined clothes-horse and ironing-board comprising a main frame provided with upper and lower brackets, clothes-frames hinged on the said main frame, and an ironing-board having pins at its inner end adapted to be hooked on the upper and lower brackets and provided with a leg, substantially as shown and described.

2. A combined clothes-horse and ironing-board comprising a main frame, an ironing-board hooked at one end to the said main frame and provided at its outer end with dovetailed cleats, a dovetail held to slide in the said cleats, a leg pivoted on the said dovetail, and a foot hinged on the lower end of the said leg, substantially as shown and described.

3. A combined clothes-horse and ironing-board comprising a main frame provided with two sets of brackets, clothes-frames hinged on the said main frame, an ironing-board provided with pins adapted to engage either set of brackets, and a leg held removably on the outer end of the said ironing-board, substantially as shown and described. 25

4. A combined clothes-horse and ironing-board comprising a main frame provided with two sets of brackets, clothes-frames hinged on the said main frame, an ironing-board provided with pins adapted to engage either set of brackets, a leg held removably on the outer end of the said ironing-board, and a button held on the said main frame to lock the said clothes-frames and ironing-board in place, substantially as shown and described. 30 35

LYDIA FAIRWEATHER.
